CLAIM

The ornamental design for a metal joist bracket, as shown.

DESCRIPTION

FIG. 1 is a top perspective view of the metal joist bracket according to the claimed design;

FIG. 2 is a bottom perspective view thereof;

FIG. 3 is a top elevation view thereof;

FIG. 4 is a bottom elevation view thereof;

FIG. 5 is a side elevation view thereof;

FIG. 6 is a side elevation view thereof;

FIG. 7 is a side elevation view thereof; and,

FIG. 8 is a side elevation view thereof.
